(57) **CLAIM**

The ornamental design for a medical instrument, as shown and described.

DESCRIPTION

FIG. 1 is a left side perspective view of a medical instrument the present invention.

FIG. 2 is a right side perspective view of the medical instrument of FIG. 1.

FIG. 3 is a top perspective view of the medical instrument of FIG. 1.

FIG. 4 is a bottom perspective view of the medical instrument of FIG. 1.

FIG. 5 is a front perspective view of the medical instrument of FIG. 1.

FIG. 6 is a rear perspective view of the medical instrument of FIG. 1; and,

FIG. 7 is a three-quarter perspective view of the medical instrument of FIG. 1.

The broken lines shown at the end of the cord and at the end of the tubular shaft represent the bounds of the claimed design; the broken lines form no part of the claimed design.

1 Claim, 7 Drawing Sheets
